UNITED STATES PATENT OFFICE.

ELIJAH BRANSON, OF GENEVA, KENTUCKY.

OBSERVATION-CAR.

1,232,761.

Specification of Letters Patent. Patented July 10, 1917.

Application filed September 18, 1915, Serial No. 51,486. Renewed January 22, 1917. Serial No. 143,884.

To all whom it may concern:

Be it known that I, ELIJAH BRANSON, a citizen of the United States, residing at Geneva, in the county of Henderson and State of Kentucky, have invented certain new and useful Improvements in Observation-Cars, of which the following is a specification, reference being had to the accompanying drawings.

10 This invention relates to an improved observation car and has for its primary object to provide a railway passenger car of this type having an improved roof construction whereby the passengers may obtain an unobstructed view of the surrounding scenery above the car without leaning from the windows, standing upon an observation platform at the end of the car, or otherwise exposing themselves to possible injury.

20 It is another and more particular object of my invention to provide an observation car having a roof consisting of a multiplicity of transparent slabs or glass plates, spaced transverse rafters to receive and support the plates and means for rigidly holding the plates upon the rafters, and shades or curtains mounted within the car adapted to be drawn under the glass roof plates to cut off the glare of the sun.

30 The invention has for a further general object to improve and simplify the construction of railway passenger cars of the above character, and provide a car which is particularly desirable and serviceable on those roads running through canyons or gorges and which will greatly add to the pleasure and enjoyment of the passengers in permitting a clear and unobstructed view of the contiguous scenery.

40 With the above and other objects in view, my invention consists in the novel features of construction, combination and arrangement of parts to be hereinafter more fully described, claimed and illustrated in the accompanying drawing, in which,

Figure 1 is a top plan view of an observation railway car constructed in accordance with the preferred embodiment of my invention;

50 Fig. 2 is a section taken on the line 2—2 of Fig. 1;

Fig. 3 is an enlarged detail section taken on the line 3—3 of Fig. 1; and

55 Fig. 4 is a detail fragmentary perspective view of one of the metal rafters.

Referring in detail to the drawing, 5 des-

ignates the sides of the car body and 6 the ends thereof. The side walls 5 of the car body are connected at their upper edges by means of a plurality of spaced transverse 60 rafters 7. Each of these rafters is of tubular sheet metal construction and of triangular shape in cross-section, as clearly shown in Fig. 3, with the apex thereof disposed downwardly. Each rafter includes 65 spaced parallel vertical portions 8 which are connected by the central or intermediate portion 9 of the rafter. From the lower ends of the vertical portions 8, the rafter 7 inclines outwardly and downwardly in opposite directions and is engaged upon the upper edge of the respective side walls 5 of the car body. These outwardly extending end portions 10 of each rafter are cut away at their extremities so as to provide projections or extensions on the top plate of the rafter, as shown at 11. These extensions rest upon the upper edges of the side walls 5 of the car, and upon these upper edges of the side walls between the ends of the rafters, the angle plates 12 of steel or other metal are arranged and secured to the side walls of the car.

The portion 7 of each rafter is provided with a central longitudinally extending rib 25 or bead 13 terminating a slight distance inwardly of the outer end of the portion 7 or more particularly the extension 11 thereof in order that an effective engagement may be had between the outer end of the rafter 11 90 and the adjacent angle plate 12. The glass slabs or plates 14 are arranged between the spaced roof rafters and rest at their edges upon said rafters against the opposite sides of the ribs or beads 13. The bolts or rods 95 15 are extended through the roof rafters 7 and through the ribs 13 thereon, the upper ends of said ribs being disposed through the plates 16 and having nuts 17 threaded upon their lower ends. By tightening these nuts 100 on the lower ends of the rods, the plates 16 may be clamped down upon the edges of the glass plates 14. In this manner, the several plates of glass may be easily and quickly secured in place upon the roof 105 rafters 7. The vertical portions 8 of the rafters and the central transverse portions 9 thereof are connected by metal or wood plates and form a central deck in the roof, as indicated at 18.

In order to exclude the rays of the sun when desired, I provide the curtains 19

which are provided with the usual spring rollers, and these rollers are mounted in suitable brackets secured to the roof structure at the lower edges of the side walls of 5 the central deck 18. The guide pulleys 20 are suitably arranged at the outer edges of the roof over which the pull cords for the curtains are trained. By simply drawing upon the cords, the curtains may be disposed beneath the glass roof plates so as to 10 effectually exclude the rays of the sun from the interior of the car. After the glass plates have been arranged upon the rafters and secured in place as above stated, the 15 clamping plates 16 may be covered with white lead or other impervious material so as to prevent the leakage of water between the edges of the metal plates 16 and the glass plates to the interior of the car.

20 From the foregoing description, taken in connection with the accompanying drawing, the construction and several advantages of the invention will be clearly and fully understood. When the car is moving through 25 a deep canyon or gorge and the passengers desire to observe the surrounding landscape above the car, it is not necessary for them to leave their respective seats, as by looking upward, they may obtain a clear and 30 unobstructed view through the glass roof plates. In observation railways as at present constructed, it is usual to provide an observation platform upon the rear of the car. The capacity of such a platform is not 35 only limited, but there is some danger of persons losing their balance and falling from the platform in the jar or vibration of the car, and also being struck by dislodged stones in the passage of the car at a 40 high rate of speed. It is apparent that a car constructed in accordance with the present invention will entirely overcome these objections in the use of an observation platform, and the passengers will be protected 45 against accidents and inclement weather, but permitting of a clear view of the surrounding scenery. When it is desired to

shut out the direct rays of the sun, it is only necessary to draw the curtains 19 in the manner above stated. It will also be 50 manifest that an observation car constructed in accordance with my invention may be manufactured at comparatively small cost and is highly convenient and serviceable in 55 actual use.

While I have shown and described the preferred construction and arrangement of the several elements employed, it is to be understood that the device is susceptible of considerable modification therein and I, therefore, reserve the privilege of resorting to all such legitimate changes as may be fairly embodied within the spirit and scope 60 of the invention as claimed.

Having thus fully described my invention, 65 what I desire to claim and secure by Letters Patent is:—

The combination with a body including side walls, of a plurality of spaced transverse rafters, each of said rafters being substantially V-shape in cross section with its apex disposed downwardly and having the outer ends of its top portion provided with extensions overlying the side walls, each of said rafters being also provided at its top 70 with an upstanding longitudinally disposed rib positioned at the transverse center thereof, the ends of said rib terminating inwardly 75 of the ends of the extensions of the beam, angle plates fixed to the outer faces of the 80 side walls and having one of their flanges extending inwardly and overlying the extended portions of the beams, transparent roof plates interposed between the rafters and seated at their edges upon the rafters at 85 opposite sides of the ribs thereof, and means carried by the rafters for holding the roof plates in applied position.

In testimony whereof I hereunto affix my signature in the presence of two witnesses. 90
ELIJAH BRANSON.
